UNITED STATES PATENT OFFICE

FRED RICKS AND ALFRED EDWARD RICHARDS, OF LEICESTER, ENGLAND, ASSIGNEES
TO UNITED SHOE MACHINERY CORPORATION, OF PATERSON, NEW JERSEY, A COR-
PORATION OF NEW JERSEY

EDGE-FINISHING MACHINE

Application filed January 9, 1928, Serial No. 245,499, and in Great Britain February 12, 1927.

This invention relates to machines for finishing the edges of sheet material, such as leather, and to that type of machine in which means is employed for shrinking or searing 5 a portion of the margin of the material.

In edge finishing leather, especially upper leather for boots and shoes, it has been found that the varying conditions encountered in the thickness of the material and in its characteristics due to differences in tanning, make it advantageous in some cases to subject the work to successive and distinct searing or shrinking operations, or to vary the intensity of the shrinking action at different points 10 upon the margin of the material. In other cases, it has been found advantageous to treat the edge of the work along lines or zones displaced transversely with respect to the edge. For example, it appears in some cases that a 15 more perfect and permanent edge finish is secured by subjecting the edge first to a preliminary shrinking operation and then following this operation after an interval by a secondary or final shrinking operation. In this way, the shape desired in the finished 20 edge may be initiated and partially secured in the first operation, while the partially formed edge may be brought down upon the body of the work and the whole edge given a smooth, compact and rounded configuration 25 in the second operation.

In those cases where the margin of the work has been prepared by a preliminary skiving operation, it has been found desirable to cause 30 one shrinking action to occur on the skived portion of the blank close to its thinned edge and a secondary shrinking action to occur along the zone of the juncture of the skived and unskived portions, thus obliterating more or less the slight ridge formed at that point. This can be effected to good advantage by a shrinking or searing action concentrated upon that part of the blank distinct from a searing action concentrated on the skived portion thereof and designed to produce the actual turning of the edge.

In one of its aspects, the present invention comprises an edge finishing machine having the capacity for handling the work in the manner above set forth. To this end, an im-

portant feature of the invention consists in shrinking means constructed and arranged to act upon the work at separate points to perform distinct shrinking operations thereon, in combination with means for effecting relative feeding movement of the work and the shrinking means. 55

In another aspect, the invention consists in an edge finishing machine having capacity for applying more effective heat and, consequently, producing a more intense shrinking action in a shorter interval than has been possible heretofore in edge finishing machines. As herein shown, this result is attained by employing a plurality of edge shrinking or 60 searing tools, each with independent provision for heat control and arranged to act progressively on the edge as it is presented to their action. We have in this manner produced a machine of high efficiency, capable of 65 operating at a higher speed than has heretofore been considered practicable and have effected a corresponding saving in the cost of 70 the edge finishing operation. 75

In another of its aspects, the present invention comprises a development and carrying-forward of machines of the type disclosed in the co-pending application for Letters Patent of the United States Serial No. 115,113, in which the work is clamped and fed in a definite predetermined path to shrinking or searing instrumentalities. As embodied in such a machine, the invention has particular utility in finishing the edges of shoe upper tips or other parts having edges fashioned on a definite center of curvature and permits the 80 operation of such machines at a high rate of speed. 85

The invention includes also within its scope a novel method of edge finishing characterized by subjecting each portion of the margin of the work to repeated shrinking operations which progressively turn the edge until it is brought over the body of the work. This novel method may be carried out by the mechanism herein shown or by any other suitable instrumentalities, being in no sense restricted to any particular form of apparatus. 90

The various features of the invention will be best understood and appreciated from the 100

following description of a preferred embodiment thereof, selected for purposes of illustration and shown in the accompanying drawings, in which

5 Fig. 1 is a view in perspective of the machine;

Fig. 2 is a plan view of the machine with parts broken away;

10 Fig. 3 is a view in perspective, on an enlarged scale, of the shrinking tools and their associated parts shown in relation to the work;

Fig. 4 is a sectional view illustrating the action of the presser roll; and

15 Fig. 5 is a sectional view illustrating the action of the skiving knife.

Before proceeding to a detail description of the machine, it will be convenient to consider first its general mode of operation. Referring to Fig. 3, a toe tip blank 100 is shown as being presented to the action of two shrinking tools located in spaced relation along the edge of the work. The tool 14 is U-shaped, with its lower member inclined slightly with 25 reference to the plane of the work. It is electrically heated and disposed adjacent to the curved face of a stationary plow 16. The edge of the work is fed past the plow 16 and in contact with the shrinking tool 14 along 30 a line or zone just within its margin. The tip blank is shown as having a skived edge 102 and is presented to the tool with its flesh side uppermost. The action of the tool 14 consists in shrinking a portion of the flesh side 35 of the blank so that the extreme margin of the work is turned or curled upwardly to an extent represented in Fig. 3 by the sectional view of the work at the left of the tool 14. A second shrinking tool 18 is located to the 40 rear of the tool 14 in the direction of feed. This is similar in shape to the tool 14 but somewhat wider so that it has a more extensive working face and is, therefore, effective for producing a more intense shrinking action upon the work. The tool 18 is located in 45 cooperative relation with respect to a plow 20, similar to the plow 16 but having a correspondingly longer acting face and being provided in addition with a turning projection 50 or horn 22. The partially formed edge of the work is advanced into range of the tool 18, which increases, intensifies and extends the shrinking operation so that the 55 edge of the work is turned or curled over the body thereof.

In treating certain kinds of leather, this secondary shrinking operation carries the edge back into contact with the surface of 60 the material; in others, the turning of the edge is assisted by the action of the projection 22 of the plow; and in all cases the turned-up edge is pressed firmly back upon the body of the blank and caused to adhere 65 to it by the action of the pressure roll 24,

which engages the edge as it leaves the secondary shrinking tool 18.

The illustrated machine comprises a table 12 which supports the various instrumentalities of the machine and is carried by a frame, not shown. The tool 14 is mounted in the forward end of an arm 26, pivotally mounted for movement about a horizontal axis between ears projecting upwardly from a circular work supporting plate 13 mounted on the table 12. The tool is secured in a pair of insulated terminals 28, clamped to the end of the arm and connected through leads 30 to a choke coil 32, having a movable core 34 by which the current flowing through the 75 tool may be regulated and the heat of the tool thereby controlled.

The normal position of the arm 26 as to height is controlled by an adjusting screw 36, which engages the work plate 13. The 85 arm carries at its forward end a presser roll 38, adapted to run upon the surface of the work as it is presented to the action of the tool 14, holding it flat and assisting in presenting it properly to the action of the tool and plow. The presser roll 38 is mounted on the clamp block 40, which carries the tool 14, and these elements are all carried by a collar mounted on the arm 26 and adjustable bodily longitudinally of the arm 26 and transversely of the work by an adjusting screw 42.

The plow 16, which cooperates with the tool 14, is mounted in the forward end of a bar 44, guided for movement transversely to the edge of the work by ways projecting from the work supporting plate 13 and adjustable in its position by means of an adjusting screw 46, mounted in a stationary bracket 48 on the work plate 13 and threaded into the rear end of the bar 44. It will be understood that by means of the adjusting screw 46 the proper relative position of the tool 14 and the plow 16 may be secured and maintained, or that the plow 16 may be shifted transversely with 100 the tool 14 when it is desired to vary the effective location of these elements with reference to the edge of the work.

The iron 18 is similarly mounted in terminals 50 projecting downwardly from a clamping block 52 carried at the forward end of an arm 54, similar to the arm 26 and similarly mounted upon the work supporting plate 13. An adjusting screw 56 determines the vertical position of the arm and an adjusting screw 58 is provided for effecting longitudinal adjustment of the tool 18 and its associated presser roll 60 upon the arm 54. The iron 18 is connected through leads 62 to a second choke coil 64, having a movable core 66 for controlling the current supplied to the iron 18 and, consequently, its degree of heat. The plow 20 is mounted in the forward end of a bar 70, guided for movement 115 by ways on the work plate 13 and adjusted 120

by means of an adjusting screw 72, mounted in a bracket 74.

The two units above described are similar in their characteristics and have each provision for independent adjustment, so that the point of action of each tool and its associated plow may be located in line with each other on the work or relatively displaced in either direction transversely to the edge 10 of the work by any desired amount. In other words, a flexibility of adjustment is provided which permits treatment of the work in the manner best suited to its characteristics.

To the rear of the secondary shrinking tool 18, in the direction of feed, is located a presser roll 24 for completing the edge finishing operation, as already explained. The roll 24 is mounted upon the forward end of a horizontal shaft 80, journaled in bearings 83 which are movably mounted upon brackets projecting upwardly from the work plate 13. The shaft carries a grooved pulley 82 between its bearings which is driven by a round belt 84. This belt is led over suitable 25 idlers to a driving pulley 86 on a shaft 88, journaled in vertical bearings in a bracket 89 projecting from the table 12 near the rear side thereof. The bearings of the shaft 80 are mounted to permit a slight vertical movement of the shaft and roll and a tension spring 81, connected to the forward bearing, is provided, as shown in Fig. 4, for pressing the roll 24 against the work with a yielding pressure. The function of the driven 30 roll 24 is to press the edge of the work as it leaves the secondary shrinking tool 18, while the material is in a more or less plastic condition, causing the turned-up edge to adhere to the surface of the work and compacting and shaping the edge.

The mechanism described to this point could be utilized to advantage with any suitable form of feeding mechanism. As already intimated, we have, however, chosen 45 to combine this mechanism with the clamp feed of such a machine as that shown in co-pending application Serial 115,113 above referred to, and this mechanism will now be described.

The table 12 has a forwardly projecting arm 90 with an upstanding boss, in which is journaled a vertical shaft 92 having an outwardly extending arm 94 with a flat work supporting plate 96 and a spring pressed clamping 50 plate 97, carried by a pivotally mounted arm 98. In Fig. 1, the work clamp is shown as located in its initial or work receiving position, a tip blank 100 having been inserted by pressing the rear end of the arm 98, locating the blank 100 properly in place and releasing the arm 98 so that the upper clamping plate 97 will engage and hold the work in position.

Keyed to the shaft 92 is a toothed segment 65 104. The work clamp may be moved by hand

from its position shown in Fig. 1 to engage the toothed segment with a driven pinion 106 fast on the upper end of a vertical shaft 108, journaled beneath the table 12 and having a driving pulley 110 fast on its lower end. This is driven through a belt 112 from a pulley 114 fast to the driving shaft 88 above referred to. It will be apparent that when the toothed segment is moved into mesh with the pinion 106, the work clamp will be swung in a counter clockwise direction into the machine, carrying the work to the various instrumentalities already described, whereby its edge is finished, and then carrying it out of range of these instrumentalities and passing out of mesh with the driving pinion 106. In such position, the finished blank may be removed and the work clamp swung by hand into re-loading position.

The machine herein shown includes also skiving means for beveling or skiving the edge of the blank to be presented to the edge finishing instrumentalities, although, as already explained, this operation is not required upon all kinds of work. The skiving means comprises a flat rotary knife 120 of the Amazeen type, mounted upon the lower end of a shaft 122 journaled in a yoke 124, adjustably mounted in a stationary bracket 126 secured to the work plate 13. The yoke 124 is connected to the bracket 126 through a curved slot which permits angular adjustment of the skiving knife 120 about the operating point, a clamping screw 128 being provided for retaining the parts in any desired position of adjustment.

The shaft 122 has a collar 130 located between the arms of the yoke 124 and backed up by a compression spring, which maintains the knife yieldingly in operating position. At its upper end, it carries a grooved pulley 132, driven by a round belt 134 from a pulley 136 secured to the upper end of the vertical driving shaft 88. The skiving knife 120 acts to bevel the edge of the blank presented to it by the work clamp, as clearly shown in Fig. 5. For guiding the work clamp accurately during the skiving operation, there is provided a supporting plate 121 projecting from the work plate 13, and also a guiding and supporting plate 95, curved at its edge to correspond to the curvature of the supporting plate 96 of the work clamp, and adapted to underlie the projecting edge of the work 100.

As already stated, the current flowing through the shrinking tools 14 and 18 is regulated and their heat controlled by choke coils 32 and 64 respectively. This equipment is designed to operate with an alternating current which is choked or impeded in its flow through each coil by the insertion of a movable core. In accordance with an important feature of the invention, we propose to reduce the current flowing through each core to a minimum except when the work is

being actually presented to the shrinking tools. To this end, the arm 140, which carries the core 34, is adjustably secured to an arm 142 projecting outwardly from a shaft 144, extending longitudinally of the machine in bearings formed at the edge of the table 12. At its forward end, the shaft 144 carries a downwardly extending arm 146 connected to a cam lever 148 through a rod 150, having a ball-and-socket joint at each end.

The cam lever 148 has, at its front end, a cam roll running upon a cam 152, carried by the vertical shaft 92. The cam 152 is of such shape that when the shaft 92 is turned by the movement of the work clamp toward operative position, the cam roll on the arm 148 will drop into a depression, permitting the cam lever 148 to swing in a clockwise direction and through the connections described, lift the core 34 out of the coil 32 so as to permit the current to flow through the coil and heat the shrinking tool 14. On the other hand, when the work clamp has progressed sufficiently to carry the work past this tool, the cam lever 148 is swung in the opposite direction and the core 34 moved into the coil 32, cutting down the current and allowing the tool 14 to cool.

The coil 64 is similarly provided with a core 66 carried by an arm 160 and connected to an operating arm 162 on a shaft 164, journaled in bearings at the other edge of the table 12. The shaft 164 carries a downwardly extending arm 166 connected through a rod 170 to a cam lever 168, operated by a second cam 172 secured to the shaft 192 below the cam 152. The operation of this mechanism is similar in controlling the flow of current through the coil 64 but is independent of the mechanism for controlling the flow of current through the coil 32 and may be adjusted to control the heat of the secondary iron 18, as desired, in timing and amount.

The vertical shaft 88, as will be apparent, serves as a common actuator for the rotary skiving knife 120, the presser roll 24, the feed clamp 96—97 and, incidentally, the heat controlling cams 152 and 172. It is shown as driven through bevel gears by a horizontal shaft 113 journaled in the bracket 89 and having a driving pulley 115 by which it may be belted to any convenient source of power.

We have outlined the general mode of operation and described the construction of the illustrated machine in detail. It will be apparent that it is admirably well suited for carrying out the novel method of edge finishing which consists broadly in subjecting each portion of the margin of the work to repeated shrinking operations. It has means also for carrying out a method characterized by an additional step of subjecting the treated edge to mechanical pressure after the final shrinking operation.

In edge finishing a tip blank such as that

shown in the drawings, the blank is first located accurately in the clamps of the feeding mechanism. The rotary skiving knife 120, the presser roll 24, and the driving pinion 106 are all driven continuously and a small current flows through the leads to the shrinking tools 14 and 18, the cores being fully inserted in the choke coils 32 and 64. The operator now swings the clamps by hand into the machine until the rotating pinion 106 meshes with the segment 104, whereupon the clamps with the work are fed continuously and uniformly to carry the margin of the tip first to the skiving knife 120, then successively to shrinking iron 14, the shrinking iron 18 and the presser roll 24. Meanwhile, the heat controlling cams 152 and 172 have acted through their connections to withdraw first the core 34 and then the core 66 from their respective coils, so that as the work reaches each iron a surge of heat occurs which lasts until the work is moved beyond the iron. As the rear end of the tip passes out of range of the presser roll 24, the segment 104 rides off the pinion 106, so that the mechanical feed terminates and the clamp with the finished tip therein comes once again under the operator's control.

Having thus described our invention, what we claim as new and desire to secure by Letters Patent is:

1. An edge finishing machine, having in combination shrinking means constructed and arranged to act upon the edge of the work at separate points to perform distinct shrinking operations thereon, and means for effecting relative feeding movement of the work and shrinking means.
2. An edge finishing machine, having in combination shrinking means constructed and arranged to act upon the work in areas of different extent located at separate points along its edge, and means for relatively feeding the work and shrinking means.
3. An edge finishing machine, having in combination a shrinking tool for performing a preliminary shrinking operation on the edge of the work, means for relatively feeding the work and tool, and means for performing a secondary shrinking operation upon the work after it leaves said shrinking tool.
4. An edge finishing machine, having in combination spaced shrinking tools, and means for feeding the work to present its edge first to one and then another of said tools.
5. An edge finishing machine, having in combination a plurality of shrinking tools having provision for relative adjustment, and means for relatively feeding the work and said tools.
6. An edge finishing machine, having in combination work feeding means, and a plurality of shrinking tools having provision

- for independent adjustment transversely to direction of feed.
7. An edge finishing machine, having in combination a shrinking tool for performing a preliminary shrinking operation on the edge of the work, a shrinking tool constructed to perform a shrinking operation of greater intensity than the first, and means for relatively feeding the work and shrinking tools.
- 10 8. An edge finishing machine, having in combination a plurality of heated shrinking tools arranged for consecutive operation upon the work, and independent heat controlling means associated with each tool.
- 15 9. An edge finishing machine, having in combination a plurality of units each comprising a shrinking tool and a plow, said units being located to act successively upon the edge of work presented to them and having provision for independent adjustment.
- 20 10. An edge finishing machine, having in combination a series of shrinking tools arranged for consecutive operation upon the work progressively to fashion its edge, and 70 pressing means constructed and arranged to act upon the edge after it has been operated upon by the last tool of the series.
- 25 11. An edge finishing machine, having in combination a plurality of heated shrinking 75 irons having work engaging portions of progressively increasing effective area and being arranged to operate successively upon the work.
- 30 12. An edge finishing machine, having in combination a plurality of units each comprising a shrinking tool and a plow, the plows having work engaging faces of progressively increasing effective area, and being arranged to operate successively upon the work.
- 35 13. In an edge finishing machine, means for feeding the work in an established path, and a plurality of edge shrinking units located along the path of the work in position to act progressively upon its edge.
- 40 14. In an edge finishing machine, a plurality of edge shrinking units, and means for clamping the work and feeding it continuously and uniformly to present its edge progressively to the action of the respective units.
- 45 15. In an edge finishing machine, a plurality of heated edge shrinking units, a clamp feed for presenting the work thereto progressively, and heat controlling mechanism acting automatically as the work advances to 80 increase the heat of the respective units.
- 50 16. In an edge finishing machine, a plurality of heated edge shrinking units, means for mechanically feeding the work to present its edge to one unit after the other, and controlling means operated simultaneously with the feeding movement of the work to produce a surge of heat in the respective units.
- 55 17. In an edge finishing machine, a plurality of heated edge shrinking units, a work feeding clamp, and a plurality of heat con- 85 trolling cams movable with the work clamp and acting to effect a surge of heat in one unit after the other as the work is fed progressively into its range.
18. In an edge finishing machine, a clamp movable to feed a tip blank about a fixed center, a rotary skiving knife, a plurality of edge shrinking units and a presser roll located along the curved path of movement of the tip blank and arranged to operate progressively upon its edge.
19. The method of edge finishing which consists in subjecting successive portions of the margin of the work to shrinking operations of progressively varying intensity.
20. The method of edge finishing which consists in subjecting the piece of work simultaneously at separated localities to a plurality of shrinking operations progressively along its edge.
21. The method of edge finishing which consists in subjecting the edge of the work simultaneously at separated localities to a plurality of shrinking operations and then pressing the shrunken edge.
